US0D1070419S

(12) **United States Design Patent** (10) **Patent No.:** **US D1,070,419 S**
Wehby et al. (45) **Date of Patent:** **** Apr. 15, 2025**

(54) **LAYERED TRAVEL PILLOW**

(71) Applicants: **Monica Wehby**, Carmel, IN (US);
Margaret Wehby, Nashville, TN (US)

(72) Inventors: **Monica Wehby**, Carmel, IN (US);
Margaret Wehby, Nashville, TN (US)

(**) Term: **15 Years**

(21) Appl. No.: **29/909,720**

(22) Filed: **Aug. 9, 2023**

(51) LOC (15) Cl. **06-09**

(52) U.S. Cl.

USPC **D6/601**

(57) **CLAIM**

The ornamental design for a layered travel pillow as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front perspective view showing our design;

FIG. 2 is a rear perspective view thereof;

FIG. 3 is a left perspective view thereof;

FIG. 4 is a bottom perspective view thereof;

FIG. 5 is a top perspective view thereof; and,

FIG. 6 is a right perspective view thereof.

1 Claim, 6 Drawing Sheets
